UNITED STATES PATENT OFFICE.

GUSTAVE E. HUTTLE, OF SCOTTDALE, PENNSYLVANIA.

SAFETY CATCH FOR MINE GATES.

Application filed February 29, 1924. Serial No. 696,074.

To all whom it may concern:

Be it known that I, GUSTAVE E. HUTTLE, a citizen of the United States, and resident of Scottdale, in the county of Westmoreland 5 and State of Pennsylvania, have invented certain new and useful Improvements in Safety Catches for Mine Gates, of which the following is a specification.

This invention relates to lifting gates and 10 more particularly to safety catches for lifting gates, such as used on mine shaft entrances and the like.

One object of the present invention is to provide a safety catch that will automatically 15 lock the gate against downward movement immediately upon the breaking or sudden release of the lifting cable.

Another object is to provide a safety catch mechanism of this class that may be readily 20 applied to existing gates without materially altering the gate construction or operating mechanism.

A further object is to provide a safety catch mechanism having as few moving 25 parts as possible, thereby eliminating wear and reducing the cost of upkeep to a minimum.

A still further object is to provide a safety catch for mine shaft gates and the like having 30 the novel construction, design, and combination of parts hereinafter described and illustrated in the accompanying drawings.

In the drawings, Figure 1 is a front elevation of a mine shaft gate having my invention applied thereto.

Figure 2 is a transverse section on the line II—II of Figure 1.

Figure 3 is a detail elevation showing one 40 of the locking plates in locking engagement with the guide posts.

Referring more particularly to the drawings, the numeral 2 designates the supporting structure or framing at the mouth of the shaft, and the numeral 3 designates the 45 fencing extending away from each side of the shaft mouth.

A pair of gate guides or posts 4 formed of pipes or rods of circular cross section are arranged vertically at each side of the entrance 50 to the shaft, and have their lower ends secured in base sleeves 5 secured to a suitable concrete or masonry base, while their upper ends are secured by suitable clips 6 to the framing 2.

55 A gate A is mounted to move vertically between the posts or guides 4 and is formed

of a series of vertical wood slats 7 secured to horizontal stringers 8, each of which has a back and front steel plate, the stringers 8 and slats 7 being secured together by 60 through-bolts 9.

Each of the stringers 8 is provided at each end with a guide encircling sleeve 10 adapted to guide the gate during its vertical movement between the guides 4. 65

A pair of safety catches B are secured on the gate A for preventing downward movement of the gate if the lifting cable should become suddenly loosened or break.

The catches B each comprise a lever 12 70 formed of a pair of metal rods, one extending on each side of the gate and secured together by bolts 13. The levers 12 are pivoted adjacent their outer ends on sleeves 14 mounted in the gate ends and held in position by bolts 15. The outer ends of the rods comprising the levers 12 are bent outwardly 75 to form spaced jaws 16.

A stop member 17 is provided on the gate A above each of the levers 12 to limit the upward movement of the levers to the horizontal. A coiled spring 19 is secured to the lower stringer of the gate below each of the levers 12 and has its upper end connected to a rod 20 which is in turn connected to the lever 12 intermediate its ends. The springs 19 are normally under tension so as to provide a constant downward pull on the levers 12. 80

A lifting rod 22 is pivotally secured to 90 the inner ends of each of the levers 12 and the upper ends of the rods 22 are pivotally connected to a cross head 23. A suitable lifting cable 24 is secured to the cross head 23 and trained upwardly and over suitable sheaves 25 on the supporting structure 2 and operatively connected with an operating cylinder 26 for raising and lowering the gate. 95

The outer ends or jaw ends of the levers 12 are provided with slots 27, and hard metal locking plates 28 having side lugs 29 are mounted between the jaws with their lugs extending into the slots 27. The plates 28 are provided with apertures 30 through which the guide posts 4 are passed. That is, the plates 28 encircle the posts 4 and are adapted to normally slide thereon. The ends of the plates 28 are bent in opposite directions at right angles to the main body of the plates and form strengthening ribs 110 or flanges 31. The plates 28 may be readily removed from the levers when they become 105

worn by loosening the bolts 13 and spreading the bars forming the levers 12.

For best results the posts 4 should be of a metal softer than the metal of the plates 28.

- 5 As will be noted in Figure 1, some of the vertical slats are cut away as at 33. These cut away portions are not essential in all gate constructions, but are found necessary in some constructions in order to provide 10 ample clearance for the downward movement of the levers 12 due to the transverse securing bolts and spacers for securing the bars forming the levers together.

In operation if the lifting mechanism 15 should suddenly break or become loose the levers 12 will be pulled down, due to the tension of the springs, thus inclining the plates 28 and causing them to wedge against and bite into the posts 4, so as to positively 20 lock the gate against falling.

I claim:—

1. The combination with a pair of cylindrical guide posts and a vertically movable gate having a sliding guide connection with 25 said posts, of means for moving said gate vertically and means for preventing the falling of said gate if said lifting means should fail, said means comprising a pair of transverse levers pivotally mounted on 30 said gate, a coil spring secured to each of said levers and to said gate for exerting a constant downward pull on said levers, a step secured to said gate above each of said levers and adapted to limit their upward movement to the horizontal, a pair of lifting rods having 35 their lower ends pivotally connected to the inner ends of said levers and having their upper ends pivotally secured to a suitable cross head, a lifting cable secured to said cross head and connected to a suitable power means for lifting said gate, said levers each being composed of two bars, one being disposed on each side of said gate, said plates having side lugs projecting through suitable slots in said jaws and having their ends bent at right angles to the main body portion of the plate to form strengthening flanges.

2. The combination with a pair of cylindrical guide posts and a vertically movable gate having a sliding guide connection with said posts, of means for moving said gate vertically and means for preventing the falling of said gate if said lifting means should fail, said means comprising a pair of transverse levers pivotally mounted on said gate, a coil spring secured to each of said levers and to said gate for exerting a constant downward pull on said levers, a stop secured to said gate above each of said levers and adapted to limit their upward movement to the horizontal, a pair of lifting rods having their lower ends pivotally connected to the inner ends of said levers and having their upper ends pivotally secured to a suitable cross head, a lifting cable secured to said cross head and connected to a suitable power means for lifting said gate, said levers each being composed of two bars, one being disposed on each side of said gate, said plates having side lugs projecting through suitable slots in said jaws and having their ends bent at right angles to the main body portion of the plate to form strengthening flanges.

2. The combination with a pair of cylindrical guide posts and a vertically movable gate having a sliding guide connection with said posts, of means for moving said gate vertically and means for preventing the falling of said gate if said lifting means should fail, said means comprising a pair of transverse levers pivotally mounted on said gate, a coil spring secured to each of said levers and to said gate for exerting a constant downward pull on said levers, a stop secured to said gate above each of said levers and adapted to limit their upward movement to the horizontal, a pair of lifting rods having their lower ends pivotally connected to the inner ends of said levers and having their upper ends pivotally secured to a suitable cross head, a lifting cable secured to said cross head and connected to a suitable power means for lifting said gate, said levers each being composed of two bars, one being disposed on each side of said gate, and a metal locking plate removably secured between said bars and encircling said posts, said plates having side lugs projecting through suitable slots in said jaws and having their ends bent at right angles to the main body portion of the plate to form strengthening flanges.

In testimony whereof I have hereunto set my hand.

GUSTAVE E. HUTTLE.
